(57) **CLAIM**

The ornamental design for a wax top for container, as shown.

DESCRIPTION

FIG. 1 is a perspective view of a wax top for container showing our new design;

FIG. 2 is a front view thereof;

FIG. 3 is a back view thereof;

FIG. 4 is a right side view thereof;

FIG. 5 is a left side view thereof;

FIG. 6 is a bottom view thereof; and,

FIG. 7 is a top view thereof.

The broken lines in the drawings depict a container and form no part of the claim.
